UNITED STATES PATENT OFFICE.

FRANK F. FORSHEE, OF MANSFIELD, OHIO, ASSIGNOR TO WESTINGHOUSE ELECTRIC & MANUFACTURING COMPANY, A CORPORATION OF PENNSYLVANIA.

DESIGN FOR A PERCOLATOR.

Application filed December 24, 1927. Serial No. 24,636. Term of patent 3½ years.

To all whom it may concern:

Be it known that I, FRANK F. FORSHEE, a citizen of the United States of America, residing at Mansfield, in the county of Richland and State of Ohio, have invented a certain new, original, and ornamental Design for Percolators, of which the following is a specification, reference being had to the accompanying drawing, forming a part hereof.

Figure 1 is a view, in front elevation, of a percolator embodying my new design,

Fig. 2 is a view in side elevation thereof,

Fig. 3 is a top plan view thereof.

Fig. 4 is a view in front elevation, and on a larger scale, of a faucet handle used with the percolator, and

Fig. 5 is a fragmentary view in front elevation, of the ornamentation on the body of the percolator.

I claim:

The ornamental design for a percolator substantially as shown.

In testimony whereof, I have hereunto subscribed my name this 9th day of Dec. 1927.

FRANK F. FORSHEE.
